Application May 17, 1937, Serial No. 142,999

17 Claims. (Cl. 91—42)

My invention relates to the general art of printing and has particular reference to the preparation of etched printing cylinders for use in rotary printing presses and the like. Such cylinders have the design or pattern to be printed reproduced in intaglio on the surface thereof, and in their preparation a photographic or other reproduction of the design or pattern to be printed is photographically transferred to the surface 5 of a suitable, smooth finished cylinder having a coating thereon of what is known as a sensitized resist solution. This coating has the property that the portions thereof which are exposed to light become relatively insoluble in water and in 10 etching solutions. Thus, when the cylinder is etched after the photographic transfer operation, the exposed portions of the cylinder coating prevent or limit the etching of those areas of the surface of the printing cylinder which correspond to the light portions of the design or pattern 15 to be reproduced.

Attempts have heretofore been made to coat printing cylinders with sensitized resist solutions of various types, but so far as I am aware, prior to the discovery of the apparatus and processes 20 set forth in my co-pending applications, S. N. 46,506 (filed October 24, 1935), and S. N. 139,706 (filed April 29, 1937), the attainment of uniform even coatings has never been successfully accomplished. Extensive tests and experimentation have established that the apparatus and 25 methods disclosed in the above identified applications constitutes a particularly satisfactory solution of the problem with reference to the coating of small and medium size printing cylinders. 30 However, while it is possible to coat large diameter cylinders such as are used in newspaper work by the methods and apparatus disclosed in these applications, some difficulty may be encountered.

The principal object of the present invention, therefore, is to provide apparatus for coating printing cylinders, particularly cylinders of large diameters, with a sensitized resist solution so as 35 to produce even coatings of uniform and controllable thickness. In its general aspects, the present application is a continuation in part of my co-pending applications, Serial Nos. 46,506 and 139,706, mentioned in the foregoing.

The invention disclosed and claimed in the 40 above mentioned co-pending applications is based on the discovery that the even and uniform coating of a printing cylinder with a sensitized resist solution or the like may be accomplished simply by applying the coating material to the

printing cylinder, and then rotating the cylinder about its longitudinal axis and also about a vertical axis generally perpendicular to the longitudinal axis during at least a portion of the period when the coating is drying and becoming 5 set. The coating may be initially applied to the cylinder when it is rotating about one or both of these axes and, if desired, the drying of the coating may be aided by the use of flow currents 10 of heated air.

I have also discovered that more satisfactory results can be obtained when using certain types of coating materials, and particularly when coating cylinders of large diameter, by varying the speeds of rotation either about the longitudinal 15 axis of the cylinder or about the axis perpendicular to the longitudinal axis of the cylinder, or both, during the drying operation. In ordinary instances the coating material will be applied to the printing cylinder when such cylinder is being rotated about its longitudinal axis at a moderate speed, although the coating material may be applied when the cylinder is being rotated about both its longitudinal axis and 20 about the axis perpendicular to its longitudinal 25 axis. At least after the coating has been applied, the cylinder will be rotated both about its longitudinal axis and about the axis which is generally perpendicular to its longitudinal axis, at a moderate speed, this rotation at moderate 30 speeds about both axes being continued for a short space of time to spread the coating evenly over the surface of the cylinder. Then it may be desirable to increase the speed of rotation of the cylinder at least about the axis perpendicular 35 to the longitudinal axis of the cylinder, which higher speed will preferably be continued throughout at least the greater portion of the drying operation. Under certain circumstances, it may also be desirable to increase the speed of 40 rotation of the cylinder about its longitudinal axis during the drying operation, as will be hereinafter made more apparent.

Other objects and advantages of my invention will be made more apparent by reference to the 45 accompanying drawings and the following description of one preferred embodiment thereof. In the drawings:

Figure 1 is a perspective view of an apparatus embodying the principles of the present invention with a printing cylinder in place therein. The covers and other closures of the device have been illustrated as opened up or cut away to make clear the several structural features;

Figure 2 is a sectional view of the coating ap- 55

paratus illustrated generally in Figure 1. The view is taken on the general line 2—2 of Figure 3;

5 Figure 3 is a sectional view on the general line 3—3 of Figure 2;

Figure 4 is a sectional view on the general line 4—4 of Figure 3. A printing cylinder is also shown in place in this figure;

10 Figure 5 is a reduced plan view of the apparatus showing the relation of the various covers; and

Figure 6 is a perspective view of the mechanism utilized for applying the coating solution to the roll.

15 Referring to the drawings, 10 designates a hollow, cast iron base upon which is mounted a fixed vertical post 11. Rotatably mounted on the post 11 by upper and lower anti-friction bearings 12 and 13 (Figure 4) is the central hub 14 of a reinforced circular table 15. A pair of pedestals 16 are rigidly mounted on opposite sides of the table 15 and are provided at their upper ends with open bearings 17 which receive and journal the ends of the supporting shaft 18 for the cylinder to be coated.

20 During the coating operation, it is highly desirable that the cylinder to be coated shall be protected from dust, and to this end the table 15 is provided with a generally cylindrically shaped housing 19 for enclosing the cylinder during the coating operation. The housing 19 is of split construction, and the upper section 20 thereof may be swung back on suitable pivots 21 to permit the cylinder to be placed within 25 or removed from the housing. Releasable clamp members 22 are provided for holding the upper and lower sections of the housing 19 together during the coating operation. The upper housing section 20 is provided with a circular opening 23 normally tightly closed by a removable cover 25 and a fine mesh screen 26, the purposes of which will hereinafter appear. If desired, the end portions of the housing 19 which engage the cylinder-supporting shaft may be provided 30 with felt sealing rings 27 or the like for assuring a tight connection between the housing and the cylinder. When such sealing rings are used, an airtight, dust proof housing for the cylinder is made possible.

35 The table 15 is rotated about its vertical axis by a variable speed, electric motor 28 mounted at one end of the stationary structure of the coating apparatus. The shaft of this motor 28 carries a pulley 29 which drives a belt 31 trained over two idler guide pulleys 32 and adapted to encircle a suitable ring member 33 supported at the periphery of the table 15. The cylinder is revolved about its longitudinal axis by a variable speed motor 34 adjustably supported upon the 40 table 15, as illustrated particularly in Figures 1 and 2. For convenience in operation, the cylinder motor 34 drives an intermediate pulley 35 which is connected to the cylinder being coated through a suitable belt 36. Collector rings 37 supported upon the bottom of the table 15 are 45 arranged to cooperate with brushes 38 for bringing power to the cylinder motor 34.

50 The revolvable table structure is enclosed within an outer housing 39 which is generally cylindrical in form and is preferably constructed of sheet metal reinforced with angle irons. The outer housing 39 is completely covered at its top by a sheet metal cover 40 which includes two oppositely arranged, hinged sections 41 and 42, as illustrated particularly in Figures 3 and 4. The

5 hinged sections 41 and 42 are provided primarily for permitting convenient access to the interior of the outer housing and to permit the cylinder to be coated to be readily located upon or removed from the table 15.

55 The central hinge section 42 is provided with a circular opening 43 which is normally partially closed by a hollow, open ended, hinged cover 44 of special design. The walls of this hollow cover 44 are insulated, and a plurality of electrical 10 heater elements 45 are located in the space therebetween. The opposite ends of the hollow cover are open, as illustrated in Figure 4. The circular opening 43 in the central cover section 42 aligns with the opening 23 in the inner housing 15 19, as is illustrated in Figures 3 and 4, the purpose of the openings 23 and 43 and the heater units 45 being to permit the introduction of heated air into the inner housing 19 during the drying of the coating. When the cover 25 for 20 the inner housing 19 is in place no air will be admitted through the openings 23 and 43, and when the cover 25 is removed to permit air to flow into the inner housing, the screen 26 serves as a filter.

25 The coating solution is applied simultaneously along the entire length of the cylinder being coated by means of an elongated, shallow tray 47 supported upon the table 15 near the bottom of the inner housing 19. A lifting mechanism 30 which includes two lifting levers 48 and an operating handle 49, as illustrated particularly in Figures 3 and 6, is provided for raising and lowering the tray 47 during the coating operation. The lifting mechanism assures that the coating 35 material shall be brought into contact with the cylinder only at the proper time. The tray 47 is also used to hold water or alcohol for washing the cylinder preparatory to the coating operation, as will hereinafter appear.

40 The inner housing 19 is maintained closed and substantially airtight during at least the initial portions of the coating applying operation. The upper section of the housing 19 is, however, provided with a pair of vent openings which may 45 be opened if desired through the actuation of automatic latches. These vent openings are illustrated at 51 in Figures 3 and 4 and are normally closed by pivoted cover members 53. The cover members 53 are biased to the open position by 50 centrifugal force when the table 15 rotates, and are held in the closed position by pivoted latches 54. The latches 54 may be readily tripped from without the inner closure 19 during the coating operation when it is desired to open the vents. 55

55 The preferred method of accomplishing the coating of a printing cylinder in accordance with my invention is substantially as follows: The cylinder to be coated is placed in the apparatus, as illustrated in Figures 1 and 4, and is connected to the cylinder motor 34 by the belt 36. The inner housing 19 is then closed, the vent covers 53 are latched in place, and the central opening 23 in the upper section 20 of the inner housing is closed by the tight cover 25. Distilled water or alcohol has previously been placed in the tray 47, and it is assumed, of course, that the surface of the cylinder to be coated has previously been carefully smoothed and prepared in the proper manner.

60 The cylinder motor 34 is then operated to 65 rotate the cylinder about its longitudinal axis at a relatively high speed. The tray 47 containing the distilled water or alcohol is thereupon raised by operation of the handle 49, and the cyl- 70

inder is washed by the water or alcohol in the tray 47. This washing operation effectively removes all dust particles or the like from the surface of the cylinder, and is of great value in assuring an even coating free from imperfections.

After washing and while the rotation of the cylinder about its longitudinal axis continues, the table 15 is rotated about its vertical axis by operation of the motor 29. This rotation of the table 15 causes the water or alcohol in the tray 47 to flow out of the ends of the tray into the inner housing 19. Suitable spouts 55 located at the ends of the housing 19 serve to carry the water or alcohol into catch buckets 57 releasably attached to the bottom of the table. After a few minutes, the tight cover 25 for the opening 23 in the inner housing is removed and the vent latches 54 are tripped to release the vent covers 53 and open the vents 51. Air, filtered by the screen 26, then circulates through the inner housing 19 and out the vents 51 as a result of the centrifugal action produced by the rotation of the table 15. To assure free circulation of air through the inner housing 19 at this time, the outer housing 39 should not be airtight. In the structure shown in the drawings, a substantial opening exists between the two hinged cover sections 41 and 42 when those sections are in the closed position (see Figure 3). Also, the opening provided in the side walls of the housing 39 for admitting the belt 31 (see Figure 2) is made considerably larger than is necessary to facilitate the egress of air.

When the roll is dry, the machine is stopped. The vents 51 are closed and the tight cover 25 is put in place. The cylinder is then ready for coating with the sensitized resist solution. The distilled water or alcohol is removed from the catch buckets 57, and the buckets are replaced in position at the bottom of the table; sections of the outer housing 39 may be opened to permit access to these buckets. A proper amount of coating solution is then poured in the tray 47 by means of a long stemmed funnel which passes through a tube guide 59 suitably located in the upper section 20 of the inner housing 19. This guide is normally closed, as by a crook. A fine mesh screen 58 located at one end of the tray 47 serves to prevent the formation of bubbles as the coating solution is poured into the tray. The funnel is removed and the guide tube 59 closed.

Next, the table motor 34 is energized to revolve the cylinder about its longitudinal axis, preferably at a relatively low speed. The tray 47 containing the coating solution is raised by operation of the handle 49, and the surface of the cylinder picks up the coating solution. After two or three revolutions of the cylinder, the tray may be lowered, although this is not absolutely necessary. Then the table motor 29 is operated to rotate the table 15 and the cylinder about the vertical axis of the device, also at a relatively slow speed. This slow speed rotation of the cylinder about both its longitudinal axis and about the vertical axis perpendicular to its longitudinal axis is continued for a few minutes, whereupon the speed of rotation about the vertical axis is gradually increased to several times its original value. At the same time, the speed of rotation of the cylinder about its longitudinal axis may likewise be increased.

The high speed rotation about both axes is continued for a sufficient time to permit the coating to begin to set, the actual time necessary to accomplish this will, of course, be determined by experiment. At this point the vent latches 54 are tripped to open the vents 51 and the cover 25

is removed, preferably without slowing down the apparatus. This permits free circulation of air through the inner housing, and in a short time the drying of the coating will be accomplished. Excess coating solution thrown off the cylinder and out of the tray 47 runs through the spouts and into the catch buckets 57 and can be re-used. In certain instances it will be desirable to heat the air admitted to the interior of the housing during the drying operation; this may readily be accomplished by energizing the heater units 45.

Briefly summarizing the operation, the cylinder to be coated is supported upon the table 15 within the housing 19. This housing is tightly closed, and the cylinder is washed in situ, preferably with distilled water or alcohol, and dried. Then, without opening the cylinder housing 19, the coating solution is introduced into the tray 47 which is located within the housing. Following this, the cylinder is rotated slowly about its own longitudinal axis, and the coating material is applied simultaneously along its entire length by raising the tray 47. Immediately following the application of the coating material, the tray 47 is lowered, and the rotation of the cylinder about the axis extending at right angles to its own longitudinal axis, i. e., the vertical axis of the apparatus, is commenced.

The rotation of the cylinder about both axes is carried out at a slow speed for a period of a few minutes. Then both speeds of rotation are slowly and uniformly increased, the speed of rotation about the axis which extends at right angles to the longitudinal axis of the cylinder being increased in the order of 15 to 20 times its original value. This high speed rotation serves to thin the film of coating material uniformly over the cylinder and is preferably continued unchanged until the coating material begins to set. At such time, filtered air is admitted to the interior of the housing 19 within which the cylinder is contained to speed up the drying of the coating and, if desired, this air may be heated. The speeds of rotation about the longitudinal axis and about the other axes are ordinarily continued unchanged during the final portions of the drying operation. When the coating is dry, the machine is stopped and the cylinder removed therefrom. The cylinder is then ready for the transfer operation whereby the design to be printed is photographically transferred to the coating thereon.

In one commercial embodiment of the invention when coating a cylinder about 14 inches in diameter, the coating solution is applied at a time when the speed of rotation of the cylinder about its own longitudinal axis is approximately 20 R. P. M. Immediately following the application of the coating material, the cylinder is rotated about the vertical axis of the apparatus at a speed of about 5 or 6 R. P. M., and these speeds are maintained for a period of approximately two to three minutes. Then the speed of rotation about the longitudinal axis of the cylinder is increased to about 60 R. P. M. or even less, and the speed of rotation about the vertical axis is gradually increased to about 100 R. P. M. These speeds are maintained for a period of approximately 10 minutes, during which time the coating sets or begins to set. The drying of the coating after the setting period does not usually require more than 4 or 5 minutes, and in this embodiment of the invention, no change in the speeds of rotation is ordinarily made during the final drying period. It will be understood, of course, that the proper speeds during each period will vary.

dependent upon the coating material used and upon the thickness desired in the finished coating. The speeds given in the foregoing are for a coating material sold under the trade name "Cold Top", which material comprises an aqueous solution of shellac containing an ammonium dichromate sensitizer. Other coating materials may well require different timing and different speeds. The exact figures can, of course, be determined by test.

In the example given in the foregoing, the cylinder is rotated both about its longitudinal axis and about the vertical axis, which is perpendicular to its longitudinal axis, during the entire period when the coating is being distributed over the surface of the cylinder and is being dried. Tests indicate that the rotation about both axes does not necessarily have to be carried on during the entire period, although it appears that the double rotation during at least a portion of the periods during which the coating is drying is of great importance in accomplishing even coating of the cylinder.

There are a number of separate, although more or less related, features which are believed responsible for the improved coating which is made possible by the apparatus of the present invention. Of particular importance in this connection is the rotation of the cylinder about its longitudinal axis and about an axis generally at right angles to the longitudinal axis during at least a portion of the drying and setting of the coating. Also, the arrangement whereby the cylinder is completely enclosed within an air-tight housing which is not much larger than the cylinder and which rotates with the table support for the cylinder is thought to be of importance in accomplishing the objects of the invention. This housing apparently prevents the generation of air currents which might tend to set the coating locally before it has spread thinly and evenly over the entire cylinder.

It also appears to be important that the speed of rotation of the cylinder about the axis extending at right angles to the longitudinal axis of the cylinder (the vertical axis of the apparatus) shall be relatively low at the early stages of the coating operation. This low speed which is gradually increased as the coating sets and becomes stronger prevents the rupturing of the film of coating material on the cylinder, while at the same time permitting the attainment of a very thin final coating, the thickness of which may be accurately controlled by variation in the speed of rotation. The particular structural arrangement of the inner or cylinder housing 19 assures that the cylinder will not be exposed to dust or other contamination between the washing, drying, and coating operations, and the vent arrangement, in combination with the filter opening through which air enters the cylinder housing during the final stages of the drying operation, permits increased speed of drying without danger of dust contamination.

The arrangement of the tray for applying the coating solution to the roll is also an important feature of the invention, for the reason that unless the coating material is applied to the cylinder at the proper instant, great difficulty will be experienced in the attainment of satisfactory distribution of that material. The screen for preventing bubbles from reaching the central portions of the tray where they might cause spots in the finished coating is another feature of importance.

The particular apparatus disclosed in the foregoing are especially suitable for coating cylinders having a diameter in excess of 7 or 8 inches and a length in excess of about 30 inches. Tests indicate that substantially all cylinders of this size can be satisfactorily accommodated if the table motion shall have a speed range of approximately 20 to 1, and if the driving motor for rotating the cylinder about its longitudinal axis shall have a speed range of approximately 3 to 1.

In accordance with the patent statutes, I have herein shown and described a form of apparatus which has been found by extensive tests to permit the satisfactory carrying out of the coating methods of the present invention. It will be understood, however, that the structural details of this apparatus and the exact sequence and timing of the steps of the method may be varied or changed in particular instances. Accordingly, it is my desire that the accompanying claims shall be accorded the broadest possible construction consistent with the language appearing therein and the prior art.

I claim the following as my invention:

1. In apparatus of the class described, a table supported for rotation about a central axis, means operable to rotate said table about said axis, means for supporting a printing cylinder or the like upon said table in such manner that said cylinder is free to rotate about its own longitudinal axis, housing means supported upon said table which may be closed about said cylinder to provide a substantially airtight enclosure therefor, means operable to apply a coating solution to said cylinder, and means operable to revolve said cylinder about its longitudinal axis during the applying operation.

2. In apparatus of the class described, a table supported for rotation about a central, vertical axis, means operable to rotate said table about said axis, means for supporting a printing cylinder or the like horizontally upon said table in such manner that said cylinder is free to rotate about its own longitudinal axis, housing means supported upon said table which may be closed about said cylinder to provide a substantially airtight enclosure therefor, means operable from without said housing to apply a coating solution to said cylinder, and means operable to revolve said cylinder about its longitudinal axis during the applying operation.

3. In apparatus of the class described, a generally horizontally arranged table supported for rotatable movement about a central, vertical axis, means operable to rotate said table about said axis, means for supporting a printing cylinder or the like in a generally horizontal position upon said table and in such manner that said cylinder is free to rotate about its longitudinal axis, a housing which is supported upon said table and which may be closed about said cylinder to provide a substantially airtight enclosure therefor, means operable to apply a coating solution to said cylinder, means operable to revolve said cylinder about its longitudinal axis during at least a portion of the coating operation, and means operable to effect the circulation of filtered air through said housing to aid in drying the coating applied to said cylinder.

4. In apparatus of the class described, a table supported for rotation about a central axis, means for supporting a printing cylinder or the like upon said table in such manner that said cylinder is free to rotate about its own longitudinal axis, means for applying a coating solution to said

cylinder comprising an elongated, relatively shallow tray adjustably supported upon said table adjacent said cylinder, and means for rotating said table about said central axis and for rotating said cylinder about its longitudinal axis.

5. In apparatus of the class described, a table supported for rotation about a central, vertical axis, means for supporting a printing cylinder or the like horizontally upon said table in such manner that said cylinder is free to rotate about its own longitudinal axis, means for applying a coating solution to said cylinder comprising an elongated, relatively shallow tray supported upon said table beneath and substantially tangential to said cylinder, means operable to raise or lower said tray, and means for rotating said table about said vertical axis and for rotating said cylinder about its longitudinal axis.

6. In apparatus of the class described, a generally horizontally arranged table supported for rotation about a central, vertical axis, means operable to rotate said table about said vertical axis, means for supporting a printing cylinder or the like horizontally upon said table in such manner that said cylinder is free to rotate about its own longitudinal axis, a housing means supported upon said table which may be closed about said cylinder to provide a substantially airtight enclosure therefor, an elongated, relatively shallow tray supported within said housing beneath said cylinder and adapted to contain the coating solution to be applied thereto, means operable from without said housing when said cylinder is located therein to raise said tray and thereby apply said coating material to said cylinder, and means operable to revolve said cylinder about its own longitudinal axis.

7. In apparatus of the class described, a table supported for rotation about a central, vertical axis, means operable to rotate said table about said axis, means for supporting a printing cylinder or the like horizontally upon said table in such manner that said cylinder is free to rotate about its own longitudinal axis, a housing supported upon said table which is adapted to receive said cylinder and which may be closed about said cylinder to provide a substantially airtight enclosure therefor, means operable to apply a coating solution to said cylinder, and means operable to revolve said cylinder about its longitudinal axis, said housing including vent openings located adjacent the ends thereof, an inlet opening located adjacent the axis of rotation of said table, cover means for said vent openings and for said inlet opening which may be removed when said table is being rotated, and a screen or filter which covers said inlet opening at least when the cover means for that opening has been removed.

8. In apparatus of the class described, a table supported for rotation about a central, vertical axis, means for supporting a printing cylinder or the like horizontally upon said table in such manner that said cylinder is free to rotate about its own longitudinal axis, a housing means supported upon said table which may be closed about said cylinder to provide a substantially airtight enclosure therefor, an elongated, relatively shallow tray supported within said housing beneath said cylinder and adapted to contain the coating solution to be applied thereto, said housing being provided with a suitably located opening whereby the coating solution may be poured into said tray without otherwise opening said housing and a cover for said opening, said tray including a fine mesh screen arranged at one end thereof for

preventing bubbles which may be formed when the coating solution is poured therein from being carried onto said cylinder during the coating operation, means operable from without said housing when said cylinder is located therein to raise said tray and thereby apply said coating material to said cylinder, and means operable to revolve said cylinder about its own longitudinal axis.

9. In apparatus of the class described, a table supported for rotation about a central vertical axis, means operable to rotate said table about said axis, means for supporting a printing cylinder or the like horizontally upon said table in such manner that said cylinder is free to rotate about its own longitudinal axis, housing means supported upon said table which may be closed about said cylinder to provide an enclosure therefor, said enclosure being substantially airtight except for air inlet and air outlet openings, and means operable to revolve said cylinder about its longitudinal axis.

10. In apparatus of the class described, a table supported for rotation about a central vertical axis, means operable to rotate said table about said axis, means for supporting a printing cylinder or the like horizontally upon said table in such manner that said cylinder is free to rotate about its own longitudinal axis, housing means supported upon said table which may be closed about said cylinder to provide an enclosure therefor, said enclosure being substantially airtight except for air outlet openings located adjacent the ends thereof and an air inlet opening located adjacent the axis of rotation of said table, and means operable to revolve said cylinder about its longitudinal axis during the applying operation.

11. In apparatus of the class described, a table supported for rotation about a central vertical axis, means operable to rotate said table about said axis, means for supporting a printing cylinder or the like horizontally upon said table in such manner that said cylinder is free to rotate about its own longitudinal axis, a housing supported upon said table which is adapted to receive said cylinder and which may be closed about said cylinder to provide a substantially airtight enclosure therefor, and means operable to revolve said cylinder about its longitudinal axis, said housing being provided with air inlet and air outlet openings and with cover means for said openings which may be removed to permit circulation of air through said housing.

12. In apparatus of the class described, a table supported for rotation about a central vertical axis, means operable to rotate said table about said axis, means for supporting a printing cylinder or the like horizontally upon said table in such manner that said cylinder is free to rotate about its own longitudinal axis, a housing supported upon said table which is adapted to receive said cylinder and which may be closed about said cylinder to provide a substantially airtight enclosure therefor, means operable to apply a coating solution to said cylinder, and means operable to revolve said cylinder about its longitudinal axis during the applying operation, said housing being provided with vent openings located adjacent the ends thereof and an air inlet located adjacent the axis of rotation of said table, and removable closure means for said vent openings.

13. In apparatus of the class described, a table supported for rotation about a central vertical axis, means operable to rotate said table about

75

- said axis, means for supporting a printing cylinder or the like horizontally upon said table in such manner that said cylinder is free to rotate about its own longitudinal axis, a housing supported upon said table which is adapted to receive said cylinder and which may be closed about said cylinder to provide a substantially airtight enclosure therefor, means operable to apply a coating solution to said cylinder, and means operable 5 to revolve said cylinder about its longitudinal axis during the applying operation, said housing being provided with vent openings located adjacent the ends thereof, an air inlet opening, and cover means for said openings which may be removed to open said inlet and vent openings when said table is being rotated.
14. In apparatus of the class described, a table supported for rotation about a central vertical axis, means operable to rotate said table about said axis, means for supporting a printing cylinder or the like horizontally upon said table in such manner that said cylinder is free to rotate 10 about its own longitudinal axis, a housing supported upon said table which is adapted to receive said cylinder and which may be closed about said cylinder to provide an enclosure therefor, said housing when closed being substantially airtight except for air outlet openings located adjacent the ends thereof and an air inlet opening located adjacent the axis of rotation of said table, means operable to apply a coating solution to said cylinder, means including a motor supported 15 upon said table operable to revolve said cylinder about its longitudinal axis during the applying operation, and an outer housing for enclosing said table, said outer housing being provided with an air inlet opening adapted to align with the air inlet opening in said inner housing during the 20 operation of said apparatus, and means for heating the air drawn into said inner housing.
15. In apparatus of the class described, a generally horizontally arranged table supported for rotation about a central vertical axis, means including bearings and a pair of pedestals rigidly mounted upon said table for supporting a printing cylinder or the like in horizontal position upon said table in such manner that said cylinder is free to rotate about its own longitudinal axis, a housing which comprises two hingedly connected complementary sections supported upon 25 said table for receiving said cylinder, said housing sections being movable into engagement with

each other so as enclose said cylinder, means for applying a coating solution to said cylinder comprising an elongated, relatively shallow tray supported within said housing beneath said cylinder and operable from without said housing when 5 said housing is closed to raise or lower said tray, and means operable to revolve said cylinder about its own longitudinal axis during the applying operation.

16. In apparatus of the class described, a table supported for rotation about a central vertical axis, means operable to rotate said table about said axis, means for supporting a printing cylinder or the like horizontally upon said table in such manner that said cylinder is free to rotate 10 about its own longitudinal axis, a housing supported upon said table which is adapted to receive said cylinder and which may be closed about said cylinder to provide a substantially airtight enclosure therefor, said housing when closed being substantially airtight except for air outlet openings located adjacent the ends thereof and an air inlet opening located adjacent the axis of rotation of said table, means operable to apply a coating solution to 15 said cylinder, means including a motor supported upon said table operable to revolve said cylinder about its longitudinal axis during the applying operation, and an outer housing for enclosing said table, said outer housing being provided with an air inlet opening adapted to align with the air inlet opening in said inner housing during the 20 operation of said apparatus, and means for heating the air drawn into said inner housing.

17. In apparatus of the class described, a table supported for rotation about a central vertical axis, means for supporting a printing cylinder or the like horizontally upon said table in such manner that said cylinder is free to rotate about its own longitudinal axis, a housing means supported upon said table which may be closed about 25 said cylinder to provide a substantially airtight enclosure therefor, means for applying a coating solution to said cylinder comprising an elongated, relatively shallow tray vertically adjustably supported upon said table beneath said cylinder, said tray being provided with a fine mesh screen located at one end thereof for preventing bubbles formed when the coating solution is poured therein from being carried onto said cylinder during the applying operation, and means operable to revolve said cylinder about its own longitudinal axis.

CHARLES L. HENDERSON.
